UNITED STATES PATENT OFFICE.

ANDREW D. DOWD, OF HOBOKEN, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,364,086.

Specification of Letters Patent.

Patented Jan. 4, 1921.

Application filed January 4, 1918. Serial No. 210,266.

To all whom it may concern:

Be it known that I, ANDREW D. DOWD, a citizen of the United States, residing at Hoboken, in the county of Hudson, State of New Jersey, have invented certain new and useful Improvements in Telegraph Systems, of which the following is a full, clear, concise, and exact description.

This invention relates to telegraph systems and particularly to printing telegraph systems that are provided with sunflower switches for connecting transmitting and receiving apparatus to telegraph circuits.

One object of the invention is to provide a printing telegraph system having a single sunflower switch at each station that shall govern the operation of the transmitting and recording apparatus at the home station and transmit to the telegraph circuit and to the associated home recorder, impulses which are selected by the transmitting apparatus.

In the printing telegraph system utilized for describing the invention, a telegraph station is provided with transmitting apparatus and a home recorder which may be connected to a duplex telegraph circuit if so desired. The transmitting apparatus embodies a keyboard or a tape transmitter for selecting the impulses to be transmitted and a series of relays for storing the selected impulses which are to be transmitted to the telegraph circuit. The recording apparatus embodies a printing recorder having a plurality of selecting magnets, which are selectively operated in accordance with the impulses selected by the transmitting apparatus.

The single figure of the accompanying drawing is a diagrammatic view of a printing telegraph system constructed in accordance with this invention.

Referring to the accompanying drawing, a sunflower switch 1 is connected to a telegraph circuit embodying conductors 2 and 3 that may be utilized if so desired for operating a polarized transmitting relay (not shown) at one terminal of a duplex telegraph circuit. The sunflower switch 1 serves to control the operation of a transmitter 4 and a recorder 5, and connects the transmitting apparatus to the telegraph circuit.

The transmitting apparatus embodies a current-control means 6, which may be a keyboard transmitter or a tape transmitter and includes a plurality of contact terminals

7, 8, 9, 10 and 11 which are selectively engaged by switch members 12, 13, 14, 15 and 16. A common switch member 17, which engages a contact terminal 18, is operated whenever any of the switch members 12 to 16 inclusive are operated. A plurality of selector relays 19, 20, 21, 22 and 23 are provided for storing the impulses which are selected by the current-control means 6. The selector relays 19 to 23, inclusive, embody energizing coils 24 to 28, inclusive, and holding coils 29 to 33, inclusive. Moreover, the selecting relays 19 to 23 inclusive, are provided with armatures 34 to 38, inclusive, for completing circuits to the sunflower switch 1 and armatures 39 to 43, inclusive, which serve to establish holding circuits for the selector relays.

The recording apparatus 5 embodies recording means 50 which includes selecting magnets or relays 51, 52, 53, 54 and 55 that are selectively operated in accordance with the impulses received from the sunflower switch 1 to select a character to be printed. A conductor 56, which is shown connected to the recording means 5, may be utilized for operating a printing magnet (not shown) or for operating any similar recording means.

The sunflower switch 1 embodies a brush arm 60 which is frictionally mounted on a constantly rotating shaft 61 and which is normally locked in an initial position by means of a latch 62. The brush arm 60 is provided with a brush 63, which bridges a contact ring 64 and contact segments 65 to 70, inclusive, and a brush 45, which connects a contact segment 71 to contact segments 72 and 73 and a contact ring 74 to contact segments 75 to 79 inclusive.

A control relay 80 having armatures 81 and 82 is provided for opening a circuit from a battery 83 through the current control means 6, and for completing a circuit from a battery 84 through a start relay 85. The start relay 85 is provided with an energizing coil 86, a holding coil 87, an armature 88 for completing a circuit from battery 89 through a start magnet 90, and an armature 91 for completing a circuit from a battery 92 through the holding coil 87, and if so desired through an operating magnet (not shown) of a tape transmitter.

A lock-out magnet 93 is provided with a holding coil 94, an operating coil 95, an

armature 96 for breaking the locking circuit of the selector relays 19 to 23, inclusive, and for establishing a holding circuit for itself from a battery 97, and an armature 5 98 for opening the circuit of the current control means 6. A relay 100, which serves the function of an overlap relay, is provided with an armature 101 for establishing a locking circuit through the lock-out relay 10 93, and an armature 102 for establishing a holding circuit from a battery 103 for itself. A line relay 105 is provided with an armature 106, for establishing circuits from a battery 107 through the printing selector 15 magnets 51 to 55 inclusive.

In the printing telegraph system utilized in describing this invention, a five-unit code made up of impulses of current and intervals of no current is used in the selection of 20 each character; and, in describing the invention, it will be assumed that the signal to be transmitted embodies the following units, namely, current impulse, three intervals of no current and a current impulse. 25 The current control means 6 is operated to select switching arms 12, 16 and 17 and completes a circuit from ground, through the switching member 17, contact terminal 18, relay 100, armature 98, armature 81, 30 where the circuit divides, one branch extending through the switch member 16, coil 28 of the selector relay 23, and the battery 83 to ground, and the second branch extending through the switch member 12, contact terminal 7, coil 24 of the selecting magnet 19, and battery 83 to ground. The relays 19 and 23 are operated and holding circuits are established from battery 83, through coils 29 and 33, the armatures 39 35 and 43, relay 80, and the armature 96 to ground.

When relay 80 is operated, the armature 81 breaks the circuit previously traced through the energizing coils 24 and 28 of 40 the selector relays 19 and 23, and the armature 82 completes a circuit from ground through the battery 84, armature 82, coil 86 of the start relay 85, contact segment 72, brush 45, and contact segment 71 to ground. 45 Thus, the start relay 85 is operated to complete a circuit from battery 89 through start magnet 90 and to establish a holding circuit for itself from the battery 92. The start magnet operates the latch member 60 to release the brush arm 60 in order to permit it to effect one revolution over the segments of the sunflower switch 1. When the brush arm 60 rotates in a counter-clockwise direction, the closed circuit which was 55 completed by the brush 63 through the ring 64, the contact segment 70, the line battery 109, and the telegraph circuits 2 and 3, is broken by the brush 63 disengaging the contact segment 70, and, as the brush 45 60 disengages contact with the contact seg-

ments 71 and 72 the circuit through the start relay is broken to deenergize the start magnet 90. The latch 62 is released and falls back into position to stop the brush arm after one revolution. The continued 70 rotation of the brush arm 60 effects the bridging of the contact segment 65 and contact ring 64 by means of the brush 63, and the bridging of the contact ring 74 and the contact segment 75 by means of the brush 75 45. The brush 63 completes a circuit that may be traced from the conductor 3 through the battery 109, relay 105, contact ring 64, the brush 63, contact segment 65, and the armature 34 of the selector magnet 19 to the 80 telegraph circuit 2. The line relay 105 is operated and a circuit is completed from battery 107 through the armature 106, contact ring 74, brush 45, contact segment 75 and the selecting magnet 51 to ground. Inasmuch as the selector magnets 20, 21 and 22 have not been operated, no impulses are transmitted to the telegraph circuit when the brush arm 60 passes over the contact segments 66, 67 and 68. However, when the 90 brush 63 engages the contact segment 69, a circuit is completed from the battery 109 through the relay 105, contact ring 64, brush 63, contact segment 69, and the armature 38 of the selector relay 23 to the 95 line conductor 2. The line relay 105 is again operated and a circuit is completed from the battery 107 through the armature 106, contact ring 74, brush 45, contact segment 79 and the selective magnet 55 to 100 ground.

The magnets 51 and 55 of the recording means 5 have been energized, and when the brush 45 of the sunflower switch 1 bridges the contact segments 71 and 73, a circuit is 105 established for effecting the printing of the selected character and for operating the lock-out relay 93 in order to release the operated selecting relays. The circuit which is completed through the lock-out relay may 110 be traced from the ground through the contact segments 71 and 73, which are bridged by brush 45, coil 95 and the battery 104 to ground. The armature 96 of the lock-out relay opens the circuit previously 115 traced from the battery 83 through the locking coils 29 and 33 of selector magnets 19 and 23, and completes a holding circuit for relay 93 in case the relay 100 is operated. The armature 98 prevents a further 120 selection by the current-control means. Thus, in case any key and the switch 17 is maintained in a closed position, a circuit is established for the relay 100 from the battery 103. Accordingly, if the lock-out relay 93 is energized when the relay 100 is in an operative position, a holding circuit is 125 established for the lock-out relay 93 from the battery 97 through the armatures 101 and 96.

Modification of the system and arrangement and location of parts may be effected within the spirit and scope of this invention, and such modifications are intended 5 to be covered by the appended claims.

What is claimed is:

1. In a printing telegraph system, the combination with a main line, a transmitter for setting up character code combinations, 10 means controlled by the said transmitter for storing the code combinations, a distributor controlled by said transmitter and adapted to transmit to line impulses corresponding to the code combinations stored 15 by said means, a relay included in the main line circuit and responsive to said line impulses, and a recording device associated with said distributor and controlled by said line relay for recording the characters represented by the line impulses.
2. In a printing telegraph system, the combination with a main line circuit, a transmitter for setting up character code combinations, relays controlled by said 25 transmitter for storing the code combinations, said relays having holding windings adapted to retain said relays in their actuated positions independently of the transmitter, a distributor controlled by said transmitter and adapted to transmit to line impulses corresponding to the code combinations stored 30 by said relays, a relay included in the main line circuit and responsive to line impulses, and a recording device associated with said distributor and controlled by said line relay for recording the characters represented by the line impulses.
3. In a printing telegraph system, the combination with a main line circuit, a 40 transmitter for setting up character code combinations, means controlled by said transmitter for storing the code combinations, comprising a series of relays each of said relays being provided with an energizing winding and a holding winding, said holding windings being adapted to retain said relays in their actuated condition independently of the transmitter, a distributor controlled by said transmitter and adapted 45 to transmit to line impulses corresponding to the code combination stored by said relays, and a recording device connected direct to said distributor and controlled thereby for recording characters represented by the code combinations stored in said relays.
4. In a printing telegraph system, the combination with a main line circuit, a transmitter for setting up character code combinations, means controlled by said 50 transmitter for storing the code combinations, a distributor controlled by said transmitter and comprising a plurality of continuous and segmented rings, a recording device also associated with said distributor,

contacts controlled by said storing means 65 and connected directly to certain of said distributor segments, a recording mechanism comprising a plurality of electro-responsive devices connected directly to certain other distributor segments and arranged to respond to the effects of the impulses transmitted to line by said distributor and determined by said storing means.

5. In a printing telegraph system, the combination with a main line circuit, a 70 transmitter for setting up character code combinations, relays controlled by said transmitter for storing the code combinations, said relays being provided with energizing circuits adapted to be closed by said 75 transmitter, said relays also being provided with holding windings whereby said relays when once actuated are retained in their actuated condition independently of said transmitter, a rotary distributor normally 80 tending to rotate, means controlled by said transmitter for releasing said distributor, whereby the code combinations stored by said relays may be transmitted to line in the form of current impulses, and a recording 85 device associated with said distributor and controlled thereby to record the characters represented by the code combinations stored in said relays.

6. In a printing telegraph system, the 90 combination with a main line circuit, a transmitter for setting up character code combinations, relays controlled by said transmitter for storing the code combinations, said relays being provided with energizing circuits adapted to be closed by said 95 transmitter, said relays also being provided with holding windings whereby said relays when once actuated are retained in their actuated condition independently of said transmitter, a rotary distributor normally 100 tending to rotate, means controlled by said transmitter for releasing said distributor whereby the code combinations stored by said relays may be transmitted to line in the form of current impulses, means controlled by said distributor for opening the holding circuits of said relays, and a recording 105 device associated with said distributor and controlled thereby to record the characters represented by the code combinations stored in said relays.

7. In a printing telegraph system, the combination with a telegraph circuit, a station connected to said circuit, transmitting 110 apparatus located at said station and comprising means for selecting code combinations and relays for storing the code combinations, a holding circuit for said relays, and recording apparatus located at said station, 115 of automatic means for opening the holding circuit of said relays under predetermined conditions, locking means for preventing a

second selection of impulses under predetermined conditions, and a sunflower switch for transmitting to the telegraph circuit, impulses corresponding to the code combinations stored by said relays, for governing the operation of the recording means and for

controlling the operation of the automatic and the holding means.

In witness whereof, I hereunto subscribe my name this 29th day of December A. D., 1917.

ANDREW D. DOWD.
